UNITED STATES PATENT OFFICE.

XAVER PFRUNDER, OF WOHLEN, SWITZERLAND.

BRAIDING MACHINE.

Application filed July 9, 1923. Serial No. 650,392.

To all whom it may concern:

Be it known that I, XAVER PFRUNDER, a citizen of the Republic of Switzerland, residing at Wohlen, Canton of Aargau, Switzerland, have invented certain new and useful Improvements in Braiding Machines, of which the following is a specification, reference being had therein to the accompanying drawing.

10 This invention relates to improvements in braiding machines without guide plates and of the type in which the drivers are provided with gear wheels for rotating the drivers, and the spool carriers are provided 15 at their lower ends with recesses with which locking means adapted to move in a substantially vertical direction co-operate, the locking means performing the transfer of the spool carriers from one driver to the 20 adjacent driver.

The present invention has for its object to provide an improved construction of a braiding machine of this type which presents several advantages over known machines, as will be fully set forth hereinafter.

According to the present invention each locking means is designed as a pin guided in the body of the gear wheel, the upper end of the pin being adapted to enter into 30 a recess formed by an annular groove provided in the lower end of the spool-carrier in order to couple the latter to the driver, and the lower end of the pin having a plate rigidly fixed to it adapted to effect the 35 transfer of the spool-carrier from one driver to the adjacent driver.

The means for guiding the pin may consist of a bore in the body of the gear wheel which bore may be arranged parallel to 40 or at an angle to the axis of the driver. A spring may be detachably connected to the locking means urging the latter in the upward direction; a simple unhooking of the spring renders it thus possible to remove 45 its locking means in the downward direction so that the number of effective locking means on a driver can be conveniently varied for the purpose of varying the pattern of the braided material.

50 Preferably means are provided for preventing a rotation of the spool-carrier during its transfer from one driver to another which are described hereinafter.

A constructional example of the subject

matter of the present invention is illustrated 55 on the accompanying drawings, in which:

Fig. 1 shows two adjacent drivers, one in elevation and the other in a vertical section, and the lower part of a spool-carrier in its position between the drivers, 60

Fig. 2 is a plan view of Fig. 1.

Fig. 3 is a part of a horizontal section along the line III—III of Fig. 1 showing the locking means and the springs,

Fig. 4 is an elevation of the driver with 65 parts shown in section along line IV—IV of Fig. 3,

Fig. 5 shows the lower part of a spool-carrier partly in elevation and partly in 70 section,

Fig. 6 is a horizontal section along line VI—VI of Fig. 5,

Fig. 7 is a view of the lower end of the spool-carrier seen from below and

Fig. 8 is a general arrangement of a 75 braiding machine provided with the improvements according to the present invention.

Referring now to the drawings, 1 denotes the base plate of the braiding machine on which base plate tubes 2 are rigidly fixed. Upon each tube 2 a driver 3 is rotatable. Each driver 3 is provided with a gear wheel 4 forming one piece with the driver, the wheels of the adjacent drivers 80 intermesh and cause adjacent drivers to rotate in opposite directions. To one or more of said gear wheels 4 rotation is imparted from a driving shaft in a known manner, the general arrangement of a braiding machine of this type is illustrated in Fig. 8 85 of the drawings. Above the gear wheel a cylindrical disk 5 is arranged which is provided at its circumference with semi-circular notches 6 for receiving the cylindrical 90 portions 7 of the spool-carrier 8 and causing thereby the latter to take part in the rotating movement of the driver. Four notches 6 are provided in the disk 5 shown in the drawing, however, a greater or 95 smaller number of notches may be provided to suit special requirements. Above the disk 5 a further disk 9 is arranged provided, with recesses 10. The disks 5 and 9 of adjacent drivers are arranged at different elevations, the lower disk 5 projects in between disks 11, 12 and 12, 13 respectively 100 provided on the spool-carrier, the vertical

distance between the disks 11, 12 and 12, 13 corresponding substantially to the thickness of the respective disks. The disk 9 of the left hand driver in Fig. 1 bears at the top the disk 13 of the spool-carrier and the disk 9 of the right hand driver projects below the disk 14 on the spool-carrier. By means of the disks 5 and 9 of the drivers and the disks 11-14 of the spool-carrier the latter is secured in its vertical position. The disks 5 and 9 of a driver are fixed to the latter by means of screw nut 15 co-operating with screw thread 15' on the driver, a set pin 16 passing through the disks 5 and 9 and penetrating into the body of the driver prevents a turning of said disks relatively to the driver. Below the gear wheel 4 a sleeve member 17 is provided having a dish-shaped enlargement 18 in its upper part. The lower end of the boss of the driver 3 fits into a cylindrical recess 17' provided in the sleeve member 17 and is secured to the latter by a set screw 19. The sleeve member 17 is supported by a base part 31 resting on the table 1. By these means the height of the driver 3 relatively to the table 1 can be adjusted by adjusting the extent to which the lower end of the driver projects into the cylindrical recess 17'.
 The means for locking the spool-carriers to one or the other of two adjacent drivers comprise the pins 20 which are guided in bores 21 provided in the body of the gear wheel. In the embodiment of the invention illustrated in the drawings the bores 21 are inclined towards the axis of the driver. To the lower end of the pin 20 a plate 22 is rigidly connected, the outer end of which is shaped as a knife edge 23 and the inner end 24 adjacent to the driver is recessed to a cylindrical surface which co-operates with the outer circumference of the dish-shaped extension 18 of the sleeve member 17 in order to prevent a turning motion of the locking means around the axis of the pin 20. The upper end of the latter is bevelled and is adapted to enter into a cylindrical recess 25 provided on the lower side of the disk 11 of the spool-carrier. The profile of the recess 25 corresponds to the inclination of the bevelled upper end of the pin 20. At the side of each pin 20 a bore 26 is provided in the body of the gear wheel in which bore a compression spring 27 is housed and which is detachably connected with the locking member, one end of the spring forming a hook 28 which enters a hole provided in the plate 22. The spring 27 tends to urge the locking means in the upward direction and said means in the disengaged position the plate rests against the surface 29 of the driver, the left hand locking means on the left hand driver of Fig. 1 is illustrated in its position when not engaging a spool carrier. 20' denotes a circular groove for lu-

bricating all the pins 20 of a driver. In order to prevent the knife-edged ends of the plates 22 of adjacent drivers from striking against each other during the rotation of the drivers, the surfaces 29 of adjacent drivers are arranged at different elevations.

In order to remove a locking means it is sufficient to disengage the end 28 of the spring, the locking means may then be drawn out in the downward direction without any dismantling of the driver.

In order to prevent a rotation of a spool-carrier during the transfer of the latter from one driver to the adjacent driver there is provided on the arbor of the spool-carrier a part 29 having the shape of a flat iron (Fig. 6); the notches 10 in the disk 9 are so shaped that two notches in the disks 9 of the adjacent drivers surround the part 29 with clearance when they register. The part 29 is made in one piece with the disk 14 and with a sleeve part 32 and the whole is slotted in the radial direction at 33 so that it can be clamped by means of the set pins 34 and 35 to the arbor 8 of the spool-carrier, over which it is pushed.

The transfer of a spool-carrier is carried out in the following manner:

In the disengaged position of the locking means, i. e. when no spool-carrier is inserted in the notch 6 of the disk 5 arranged above the locking means, the latter is pressed by the action of the spring in the upward direction so that the upper face of the plate 22 bears against the face 29 of the driver. The insertion of a spool-carrier into a driver is effected by pushing the spool-carrier sidewise upon the disks 5 and 9 whereby the bevelled edge 30 of the disk 11 glides over the bevelled end of the pin 20 and causes a displacement of the latter in the downward direction against the action of the spring 27. Toward the end of this sidewise movement, when the spool-carrier has fully entered the notch 6 the pin 20, under the action of its spring, enters into the circular groove 25. The bevelled end of the pin 20 abuts against the bottom of the groove 25 and the upward movement of the pin is limited thereby. In Fig. 1 the locking means of the right hand driver is illustrated in this position and it will be seen from the drawing that with the locking means in this position the plate 22 does not bear against the surface 29 of the driver but is at a lower level.

When a spool-carrier locked to one of the drivers is carried around to the adjacent driver the locking means of the first driver comes into co-operation with the disengaged locking means of the other driver. Thereby the knife edge 23 of the plate 22 of the disengaged means is pushed over the knife edge of the plate 22 of the means engaging the spool carrier and causes a displacement of the latter in the downward direction.

The pin 20 of the previously engaged locking means is withdrawn from the groove 25 and upon the further rotary movement of the drivers the pin 20 of the previously disengaged locking means enters into the circular groove of the spool-carrier, whereby the latter is locked to the adjacent driver.

The thickness of the disks 5 and 9 can be so chosen that the lower disk 5 of a 10 driver is made thicker than the disk 5 of an adjacent driver which is at a higher elevation, the vertical distance between discs 11 and 12 on the spool-carrier being chosen larger than the vertical distance between the 15 disks 12 and 13 of the spool-carrier to correspond to the difference in the thickness of the disks 5. The disks 9 are made thinner than the thinner one of the disks 5. Thereby the advantage is obtained that the thickness 20 of the disks 5 after it has been worn, may be ground and thereafter be inserted to replace a thinner disk 5 of an adjacent driver, whilst the worn thinner disk 5 of the latter can be worked to the shape and 25 thickness of the disk 9. The securing of the disks by means of a screw joint to the driver permits a convenient exchange of said disks.

In order to prevent waste material from 30 lodging in the bore 26 in which the spring 27 is arranged a cover 36, as indicated in Fig. 4, may be provided for closing said bore.

With the braiding machine according to 35 the present invention the possibility of making the driver and its gear wheel of one piece, i. e. to cast them in one piece, implies a considerable simplification and reduction in the costs of manufacturing a braiding 40 machine; furthermore the undesirable disarranging or getting loose of the gear wheel on the driver is thus avoided.

Further advantages over the known braiding machines are the following: A short 45 movement and a good guidance of the locking means, the guide rod of the locking means forms itself the member which locks the spool-carrier, a secure action of the locking means with the circular groove in the 50 spool-carrier is always ensured, the locking means work therefore always in a reliable manner when the machine runs at high speeds. The locking means are operative for both directions of rotation of the 55 machine. Locking means and springs are protected against waste material and therefore work reliably. The fact that when the locking means engages a spool carrier and the end of the pin abuts against the bottom of 60 the groove, makes the provision of a separate stop for restricting the upward movement of the pin of the loaded locking means superfluous. By a single grip the locking means can be removed without it being necessary to dismantle the driver, whereby 65

a great saving of time and an increased output results when the pattern of the braid has to be changed frequently.

The securing of the disk to the driver by means of a screw joint is a considerable 70 advantage over the known method for riveting the disks to the drivers as it permits a convenient exchange of the worn disks.

I claim:

1. In a braiding machine, the combination 75 with a plurality of spool-carriers each having a circular recess provided in their lower ends, of drivers provided with gear wheels and with notches for the reception of the spool-carriers, and locking means comprising a pin guided in the body of the gear wheel, the upper end of said pin adapted to enter into the circular recess of a spool-carrier and the lower end having a plate rigidly fixed thereto for operating the locking 80 means and effecting the transfer of a spool-carrier from one driver to an adjacent driver.

2. In a braiding machine, the combination 90 with a plurality of spool-carriers each having a circular recess provided in their lower ends, of drivers provided with gear wheels made in one piece with the drivers and with notches for the reception of the spool-carriers, and locking means comprising a pin guided in the body of the gear wheel, the upper end of said pin adapted to enter into the circular recess of a spool-carrier and the lower end having a plate rigidly fixed thereto for operating a co-operating 95 locking means and effecting the transfer of a spool-carrier from one driver to an adjacent driver.

3. In a braiding machine, the combination 100 with a plurality of spool-carriers each having a circular recess provided in their lower ends, of drivers provided with gear wheels made in one piece with the drivers and with notches for the reception of the spool-carriers, and locking means comprising a pin guided in a bore provided in the body of the gear wheel at an angle to the axis of the driver, the upper end of said pin adapted to enter into the circular recess of a spool-carrier and the lower end having a plate rigidly fixed thereto for operating the locking 110 means of an adjacent driver and thereby effecting the transfer of a spool-carrier 115 from one driver to an adjacent driver.

4. In a braiding machine, the combination 120 with a plurality of spool-carriers each having a circular recess provided in their lower ends, of drivers provided with gear wheels made in one piece with the drivers, and with notches for the reception of the spool-carriers, and locking means comprising a pin guided in a bore provided in the body of the gear wheel at an angle to the axis of the driver, a spring arranged at the side of the pin and detachably connected to the 125 130

locking means and adapted to urge the latter in the upward direction for causing the upper end of said pin to enter into the circular recess of a spool-carrier, and a plate 5 rigidly fixed to the lower end of said pin for operating the locking means and effecting the transfer of a spool-carrier from one driver to an adjacent driver.

5. In a braiding machine, the combination 10 with a plurality of spool-carriers each having a circular recess provided in their lower ends, of drivers provided with gear wheels made in one piece with the drivers, disks connected to said drivers by means of a 15 screw joint and provided with notches for the reception of the spool-carriers, and locking means comprising a pin guided in a bore provided in the body of the gear wheel at an angle to the axis of a driver, the upper 20 end of said pin adapted to enter into the circular recess of a spool-carrier and the lower end having a plate rigidly fixed thereto for operating the locking means and effecting the transfer of a spool-carrier from 25 one driver to an adjacent driver.

6. In a braiding machine, the combination 30 with a plurality of spool-carriers each having a circular recess provided in their lower ends, of drivers provided with gear wheels made in one piece with the drivers, disks connected to said drivers by means of a 35 screw joint and provided with notches for the reception of the spool-carriers, and locking means comprising a pin guided in a bore provided in the body of the gear wheel at an angle to the axis of the driver, a spring arranged at the side of the pin and detachably connected to the locking means and adapted to urge the latter in the upward 40 direction for causing the upper end of said pin to enter into the circular recess of a spool-carrier, and a plate rigidly fixed to

the lower end of said pin for operating the locking means to permit the transfer of a spool-carrier from one driver to an adjacent 45 driver.

7. In a braiding machine, the combination 50 with a plurality of spool-carriers each having a circular recess provided in their lower ends, of drivers provided with gear wheels made in one piece with the drivers, disks connected to said drivers by means of a screw joint and provided with notches for the reception of the spool-carriers, a sleeve member provided below each driver and 55 having a cylindrical bore, the lower end of the driver fitting and projecting into said bore to a greater or smaller extent for adjusting the elevation of the drivers, and locking means comprising a pin guided in a bore 60 provided in the body of the gear wheel at an angle to the axis of the driver, the upper end of said pin adapted to enter into the circular recess of a spool-carrier and the lower end having a plate rigidly 65 fixed thereto for operating the locking means and effecting the transfer of a spool-carrier from one driver to an adjacent driver.

8. In a braiding machine, the combination 70 with a plurality of spool carriers each having a circular recess; of notched drivers for the reception of said carriers, gear wheels on the drivers and depressible pins movable with the carriers and arranged to enter said 75 circular recesses and hold the carriers in the notches of the drivers, and means on the lower ends of said pins arranged to co-operate when adjacent drivers move to transferring position to release the spool carrier 80 from one driver and transfer it to the other.

In testimony whereof I affix my signature,

XAVER PFRUNDER.
